UNITED STATES PATENT OFFICE.

ANDREW McWILLIAMS, OF HAZZARD, PENNSYLVANIA.

AUTOMATIC APPARATUS FOR OPENING AND CLOSING DOORS.

SPECIFICATION forming part of Letters Patent No. 432,210, dated July 15, 1890.

Application filed February 1, 1890. Serial No. 338,912. (No model.)

To all whom it may concern:

Be it known that I, ANDREW McWILLIAMS, a citizen of the United States, residing at Hazard, in the county of Mercer and State of Pennsylvania, have invented certain new and useful Improvements in Automatic Apparatus for Opening and Closing Doors in Mines, &c.; and I do hereby declare the following to be a full, clear, and exact description of the invention, such as will enable others skilled in the art to which it pertains to make and use the same, reference being had to the accompanying drawings, which form a part of this specification.

15 My invention relates to an improved ventilating-door for coal-mines; and it consists in a device whereby a car moving along the track will automatically open and close the door, as will be fully described hereinafter.

20 In the accompanying drawings, Figure 1 is a plan view of my improved device for opening and closing mine-doors. Fig. 2 is an enlarged view of the device for locking the door when open. Fig. 3 is an elevation of one of 25 the counter-weights employed to keep the levers in the path of the moving car.

To put my invention into practice, I construct a door *a* and hinge the same to a suitable vertical post *b* in a manner that the same 30 will open either way. At each side of this door *a* and a short distance away are pivoted two bent levers *c*, having one end of each projecting over the track *d* and within reach of a moving car *e*. These levers *c* are pivoted 35 at their inner ends *f*, and are provided with a groove or channel *o*, (see Fig. 3,) running or extending from its pivotal point *f* around the curved portion of the levers *c*.

g designate two cords or ropes, which are 40 secured at one end to the door *a*, and after passing around pulleys *h* and through the grooves *o* in the curved portion of the levers *c* are secured at their other ends to the pivots *f* of said levers. To the levers *c* at a point 45 intermediate of their length are connected weights *i*, which serve to keep said levers in the path of moving cars to automatically open the door *a*.

At one side of the track *d*, near the door *a*, is an upwardly-projecting pivoted bar *k*, which 50 extends above and lies close to the rail *d* in a manner that the wheels of the moving truck will push the same to one side. (See dotted lines, Fig. 2.) Rigidly attached to this bar *k* is a horizontal catch *l*, which will hold the 55 door open until the car passes through.

The operation of my invention is as follows: The forward wheel of a car *e*, moving along the track *d*, strikes the outer end of one of the levers *c* and moves it in the direction indicated by the arrow in Fig. 1. This movement of the lever *c* draws the cord *g* around the pulleys *h*, and thus opens the door *a*. The door *a* passes over the bar *k* and is kept from returning to its closed position by the stop *l*. 65 As the car passes through the open door its wheels cause the bar *k* to turn, and this depresses the stop *l*, so that the door, which is suitably hung for that purpose, may return to its closed position after the car has passed. 70 The door is kept from coming in contact with the car while in its open position by the curved bar *p*, which bears against the side of the car as it passes.

What I claim, and desire to secure by Letters Patent, is—

The herein-described apparatus for opening and closing mine-ventilating doors, consisting of the levers *c*, projecting within reach of the car and provided with a curved grooved 80 portion and adapted to operate a rope or cord secured over suitable pulleys *h* and attached to the mine-door, suitable counter-weights *i*, and a device for locking and releasing the door after the car passes a given point, substantially as and for the purpose described. 85

In testimony that I claim the foregoing I hereunto affix my signature this 19th day of November, A. D. 1889.

ANDREW McWILLIAMS. [L. S.]

In presence of—

M. E. HARRISON,
H. H. SALLADE.
